UNITED STATES PATENT OFFICE.

EZRA T. GILLILAND, OF BOSTON, MASSACHUSETTS.

ELECTRICAL CONTACT-POINT.

SPECIFICATION forming part of Letters Patent No. 324,678, dated August 18, 1885.

Application filed May 15, 1885. (No model.)

To all whom it may concern:

Be it known that I, EZRA T. GILLILAND, residing at Boston, in the county of Suffolk and State of Massachusetts, have invented certain 5 Improvements in Electrical Contact-Points, of which the following is a specification.

My invention relates to electrical contact-points for divided electrical circuits, as employed in telephonic and other electrical instruments. These electrical contacts as usually constructed are of two classes. In one form the two points are simply brought together and there held by spring-pressure or an equivalent. In the other, called the "sliding contact," one point, before coming to rest, slides or scrapes along upon the surface of the second. Both forms are defective, as the interposition of dust and other insulating substances is not prevented, and this often results 15 in a complete failure in the operation of instruments depending thereon. In telephonic apparatus as at present constructed for public use those defects in contact-points or circuit-closers frequently cause the telephone set 20 to become inoperative. To the end that these difficulties may be remedied, I have invented improved contact-points or circuit-closers for use on the switch-arm employed in telephone 25 outifts.

The improvement consists in providing one contact-point or electrode with one or more points or projections placed in position to precede the contact-point proper in a movement across the face of its complementary electrode, 30 thus scraping and cleaning the surface of such electrode and preparing a clean surface upon which the contact-point proper may rest. The two contact-points are formed of metal or other good conductor. The additional points 35 or projections may be of the same material or not.

The accompanying drawings illustrate the invention.

Figure 1 shows a magneto-generator and bell having a gravity switch-arm to which my improved contact-points are applied. Fig. 2 45 is a detached view of the gravity-arm and contact-points in their relative position.

Magneto bell sets for telephonic purposes

are usually equipped with four circuit-closing 50 points. I will illustrate my invention by reference to one point, as they are all substantially alike. One contact or electrode of a pair is preferably fixed, and consists of a spring, *s*, curved at the point of contact with its complementary electrode, *a*. I construct 55 this electrode *a* in two divisions, or I form it with two or more edges, corners, or projections, or place one or more points or projections beside the contact-point proper, preceding 60 it in the line of movement imparted to it by the movable support *G*, so that one or more edges or projections pass across the face of contact *s* at every movement of the support. A very effective construction is shown in the 65 drawings, where the contact *a* is cylindrical, and has a segment removed from its periphery, forming two sharp edges or projections, *b c*. When the support *G* is at its lowest extremity, *a* and *s* are completely separated; but as support *G* moves toward its upper limit the edge 70 *b* of electrode *a* first scrapes or brushes the surface of electrode *s*, and the edge *c*, following *b*, takes up its position on surface *s*, thus cleaned by the edge or projection *b* preceding it. Thus any dust or dirt settling upon *s* is scraped or brushed from its surface 75 and carried out of reach of the edge or contact proper, *c*.

What I claim, and desire to secure by Letters Patent, is—

1. The combination of a fixed contact-point and a contact-point having two or more edges or projections located upon a switch-arm in position to slide or scrape across or upon the face of the first-named contact whenever said arm is actuated.

2. A fixed contact point or projection and a contact point or projection located upon a movable arm, combined with one or more additional points or projections, also placed in said movable arm in position to precede the contact-point in its movement across or upon the face of the fixed point or projection, so as to brush or scrape the surface of the latter.

3. A magneto-generator having a movable switch-arm provided with one or more pairs

of contact-points, composed of a fixed point or surface, and a point or projection located upon the said arm, combined with one or more points or projections preceding the last-named contact in its movement upon or across the

name to this specification, in the presence of two subscribing witnesses, this 13th day of May, 1885.
